UNITED STATES PATENT OFFICE.

JULIUS L. CABLE, OF BOSTON, MASSACHUSETTS.

CUSHION SUPPORT.

Application filed July 8, 1924. Serial No. 724,903.

This invention relates to that class of seat or cushion supports in which a series of coiled springs, having coils of uniform diameter, are arranged side by side with their adjacent coils connected to hold them in proximity. In this class of devices, it has been the practice to enclose each spring in a textile casing, principally to limit the expansion thereof to a uniform extent, and, prior to my invention, it has been customary, in doing this, to divide an elongated cloth bag into compartments by transverse rows of stitches, and then to pass the end of a wire spring through the material into each compartment and screw it into the same by turning the spring about its center line. On account of the difficulty of performing this last operation, this method has been found to be expensive to an objectionable extent. Moreover, while a single row of springs will be connected by the cloth, when this method is employed, the connection of a series of rows of springs side by side is not convenient, or at least no convenient method of connecting the rows has been devised, so far as I am aware.

The object of my invention is, principally, to provide an improved means and method of enclosing springs of the character above referred to in a cloth casing, which will be simple, effective, and durable, as compared with previous methods and constructions and which will enable the encased springs to be readily attached to each other, so as to form a yielding surface of any desired area.

I accomplish this object in the manner hereinafter described, and as illustrated in the accompanying drawing in which:

Fig. 1 is a plan view of a series of springs constructed in accordance with my invention.

Figs. 2 to 7 inclusive illustrate successive stages in the process of encasing a spring and

Fig. 8 is a sectional view of the encased spring.

In applying a textile casing to any one of the series of coiled wire springs 1, the coils of which are of approximately uniform diameter, the spring is first compressed until its coils lie in close proximity, or practically in contact, and they are then temporarily fastened together in this position by any convenient means as by a pair of wires having hooks at each end, as shown in Fig. 2.

A rectangularly shaped textile section 3, which, in the present instance, will be of light weight, such as cheese cloth, is provided, the width of which is somewhat greater than twice the height of length of the spring when expanded to the desired extent, and the length of which is slightly greater than the length of the periphery of the spring. In assembling the spring and cloth section thus provided, the latter is first passed through the collapsed spring coil, as shown in Fig. 3 and then doubled about one side portion thereof. The end portions are then laid one on the other and sewed together in a sewing machine by a row of stitches 4, as indicated in Figs. 4 and 5. This may be readily accomplished by reason of the collapsed condition of the spring and the result consists in the formation of the cloth into a tubular casing, in which the spring is located.

The hooks 2, are then removed from the spring, permitting it to expand until the tubular casing is drawn tight between the end coils of the spring, as shown in Figs. 6 and 8. The casing is then drawn over the spring until its ends meet and the coils are completely covered. The casing ends may then be fastened together if desired, but this is usually unnecessary. By this arrangement the spring will be completely enclosed by a casing which lies against its exterior and interior peripheries and the expansion of the spring beyond a certain point will be restrained at all points by two plies of the cloth. When the spring is distended the connecting seam 4 of the casing will usually be held midway of the ends of the spring, as shown in Figs. 6, 7 and 8, although the particular position in which it is located is immaterial.

In making up a spring support for a cushion or the like with springs, each of which is enclosed by a textile casing as above described, the springs are preferably bound together by passing a twine through them successively and knotting it after binding each pair. Several series of springs, bound together in this manner, side by side in a row, are placed side by side and bound together in a similar manner so as to form a yielding support of the desired area as indicated in Fig. 1.

I claim—

The process of enclosing a coiled spring in a textile casing, which consists in pro-

viding a strip of textile material of a length as great as twice the height of the spring when normally restrained and of a width approximating to the periphery thereof, passing the strip through the interior of the spring from end to end, collapsing the spring and drawing the end portions of the strip together exteriorly of the spring and at one side thereof and sewing them together

while the spring is held collapsed, and then drawing the tubular casing thus formed about the spring to enclose the same and hold it under predetermined restraint when released.

In testimony whereof, I have signed my name to this specification.

JULIUS L. CABLE.
